[57] CLAIM

The ornamental design of a floorplate for gooseneck hitch assembly, as shown and described.

DESCRIPTION

FIG. 1 is a perspective view of the floorplate for gooseneck hitch assembly;
FIG. 2 is a right side elevational view; the left side elevational view being a mirror image thereof;
FIG. 3 is a rear elevational view thereof;
FIG. 4 is a front elevational view thereof;
FIG. 5 is a bottom plan view thereof; and,
FIG. 6 is a top plan view thereof.

In the drawings, the broken lines representing apertures in the surface of the floorplate define the boundaries of the claim and form no part thereof; the broken lines representing structure extending below the floorplate are for illustrative purposes only and form no part of the claimed design.
